CLAIM

The ornamental design for a basketball stands with sports net as shown and described.

DESCRIPTION

FIG. 1 is a front, left, and top perspective view of the basketball stands with sports net, showing my new design. FIG. 2 is a rear, right and bottom perspective view thereof. FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of the area labeled 9 in FIG. 1.

FIG. 10 is an enlarged view of the area labeled 10 in FIG. 1.

FIG. 11 is an enlarged view of the area labeled 11 in FIG. 1.

FIG. 12 is an enlarged view of the area labeled 12 in FIG. 2; and,

FIG. 13 is an enlarged view of the area labeled 13 in FIG. 2.

The broken lines depict portions of the basketball stands with sports net form no part of the claimed design. The dash dot dash broken lines of the basketball stands with sports net in FIGS. 1 and 2 illustrate a boundary and cut line of the enlarged views in FIGS. 9 and 13 and form no part of the claimed design.

The appearance of any portion of the basketball stands with sports net shown between the break lines forms no part of the claimed design.
